UNITED STATES PATENT OFFICE.

FRANCIS LEONARD ORR, OF THURMAN, IOWA, ASSIGNOR, BY DIRECT AND MESNE ASSIGNMENTS, TO ORR GAS ENGINE STARTER COMPANY, OF OMAHA, NEBRASKA.

ENGINE-STARTER.

No. 837,953.

Specification of Letters Patent.

Patented Dec. 11, 1906.

Application filed September 7, 1905. Serial No. 277,569.

To all whom it may concern:

Be it known that I, FRANCIS LEONARD ORR, a citizen of the United States, and a resident of Thurman, in the county of Fremont and State of Iowa, have invented a new and Improved Engine-Start, of which the following is a specification.

My invention relates to starters for engines, more particularly of the internal-combustion type, and has for its object novel and improved means adapted for use with any type of similar engine, whereby with power stored into a suitable receiver the engine may be effectively started from any point of rest of its crank-shaft.

The invention consists of peculiar devices and apparatus whereby a portion of the exploded or exhaust gases may be stored under pressure and the same employed, by means of the peculiar devices, for starting the engine regardless of the position of the engine-piston.

In the following detail description of my invention reference is had to the accompanying drawings, in which—

Figure 1 is a view illustrating my invention in use, a sectional portion of the engine-cylinder, with its piston, being only shown in the view; and Fig. 2 is a detail end view in illustration of the compression-valve-operating devices.

In the practice of my invention I employ a suitable tank A and connect it by means of a suitable tubular passage-way B with the combustion end of the engine-cylinder C. In the passage-way B, I arrange any form of compression-valve D, having a projecting stem E. Above the valve-stem E, I locate a cam F, having its outer side made conical or inclined, substantially as indicated at G. The cam is arranged on a shaft H, driven through any well-known gearing or other mechanical devices (not shown) coupling it with the engine crank-shaft I. In further carrying out my invention I employ a tubular passage-way J, sufficiently smaller than the passage-way B. The passage-way J is arranged with one end in open communication with the receiving end of the tube B and its other end connected with the tank A, as shown. In the reduced passage-way J, I arrange any form of check-valve K, seating as indicated by the arrow.

L denotes an opened cylinder, made communicating with the storage-tank A through a tubular passage-way M. In the latter passage-way I arrange a three-way valve N, having a working handle O and with one opening therethrough adapted for discharge into the open air at P, as will be fully understood without illustration or detail description thereof. In the cylinder L, I arrange a piston Q, having a rod R, whose upper or outer end is provided with rack-teeth S.

The outer end of the piston-rod R is suitably supported and provided with the rack-teeth S thereon, in engagement with similar teeth on a segmental gear T, arranged to turn freely on the crank-shaft I. A suitable pawl or dog U is provided on the loose gear T, with the same designed for engaging the teeth of a ratchet-wheel V, fixedly secured to the crank-shaft against its rotation thereon.

For use in connection with the devices last described I provide a fixedly-supported finger W, with its free end W' extended and disposed suitably for engaging the pawl or dog U, whereby should the engine be started into reverse or backward rotation the pawl will be thrown from engagement with the teeth of the ratchet-wheel V. The finger W may be located on an arm A' at the upper end of a suitable standard A², projecting from the engine-bed.

B' denotes a bell-crank having oscillating support at B² on a projection A³ from the standard A². It will be noticed that one end B³ of the bell-crank has pivotal connection with the piston-rod R and that its other end B⁴ is disposed for attachment to the adjacent end of a rod C'. In further describing my invention I would refer to an elongated pin D', which may have support on the rear end of the engine-cylinder C. On this pin I slidably arrange an arm E', through which the adjacent end of the rod C' is extended and secured by jam-nuts F'. The free end of the arm E' is provided with a roller G' and its under side disposed resting on the upper end of the valve-pin E with sliding contact, as will be understood.

The construction of my invention will be understood from the above description.

In Fig. 1 of the drawings all the parts of my invention are shown at normal position. The engine may be stated as standing at rest.

with its piston H' left at the middle of cylinder C.

In the use of my invention exhaust-gas or explosive mixture is stored in the tank A under pressure. This may be accomplished by passage of a portion of the exhaust-gas into the tank through the pipe J. A check-valve K is arranged in this pipe to prevent return passage therethrough of the gas stored in the tank. Now when it is desired to start the engine in motion the three-way valve N is turned, closing the opening P therethrough to open air and at the same time opening up free passage-way through the pipe M from the tank A to and into the cylinder L under its piston Q. Power thus introduced into the cylinder L will force the piston Q upwardly and through operation of the latter's rod E, the rack S, toothed segment T, pawl U, and ratchet-wheel V impart boosting action to the shaft I, and thereby start rotation of the power-shaft I. When the boosting action of the power-shaft just described is made, should the shaft be started into backward rotation, owing to position of its crank or from other reason, the free end W' of the finger W will engage the pawl U and lift its free end out of engagement with the teeth of the ratchet-wheel V. Now the segment T being free to turn on the shaft I it is apparent that further boosting action of the shaft I cannot be made until the engine comes to rest and at which time the boosting operation may be repeated, starting the power-shaft forward, as will be understood. Upon effecting the boosting action now fully described the bell-crank B' through attachment of one end B³ thereof to the rack end of the piston-rod R and connection of its other end 40 B⁴ with the adjacent end of a rod C' valve D in the pipe B opens, as will be described further on. It is intended that upon opening the valve D sufficient pressure of gas shall pass from the tank A, through the pipe B, and into the combustion-chamber of the cylinder C to force forward the engine-piston, and thus start the engine in operation. Endwise movement of the rod C' taking place upon operation of the bell-crank B' during 50 the boosting action described will adjust the arm E' on its supporting-pin D' to position, with the roller G' thereon directly under the double cam F, and the roller G' is assured of proper movement into adjusted position through means of the outer conical-shaped surface G on the cam. Now the cam-shaft H having proper gearing or other driving connection with the engine power-shaft, it is apparent that upon continued operation of 60 the cam F and at proper time its action will effect downward movement of the free end of the arm E' and through pushing action of the latter against the upper end of the valve-stem E force open the valve, whereupon pressure and volume of gas will rush through the

pipe B into the combustion-chamber of the cylinder C at each return stroke of the engine-piston for effectively starting the engine. In further description of my invention it becomes necessary to say that when the engine has been started and is under sufficient momentum the handle O is turned, adjusting the passage-ways through the valve N, providing free passage-way from the under side of the piston Q in the cylinder L, 70 through the pipe M and opening P of the valve N, to the open air. This operation cuts off flow of gas from the tank A. Now pressure being removed from the under side of the piston Q, it is apparent that the latter will 80 by gravity thereof and its connected devices be returned to normal position at the lower end of the cylinder L. The action of parts just described will through the bell-crank B' and rod C' force the arm E' from under the cam F to normal position. (Illustrated in Fig. 1 of my drawings.) It will be understood that after manipulation and operation of the starting means above described the regular or ordinary power means is used, as 90 with any engine of this character.

While the means hereinbefore described is effective for automatic operation of the valve D, I do not desire to be restricted thereto, since the same may be materially modified 95 and still remain within the scope of my invention, which may be stated as comprehending broadly the use of a storage-tank, means whereby the engine exhaust-gases or unexploded mixture may be stored therein by action of the engine-piston and devices where-through a valve in a passage-way connecting the tank and engine-cylinder is opened and closed for governing feed of the stored gases into the engine-cylinder. 105

Having thus described my invention, what I claim as new, and desire to secure by Letters Patent, is—

1. The combination with the cylinder and piston of an engine, of a storage-tank, tubular passage-ways providing communication between the engine-cylinder and tank, a check-valve in one of said tubular passage-ways, a controller-valve in a separate similar passage-way, a cylinder having independent communicating passage-way with the storage-tank, a valve in the latter passage-way, having an exit-opening leading to the outer air, a piston in the latter cylinder, having a suitably-extended rod, means operatively connecting the piston-rod with the engine power-shaft, whereby the same may be given boosting action, and means operatively connecting the boosting devices with the controller-valve, substantially as described. 110

2. The combination in an engine-starter, of a suitable tank, a passage-way leading from the tank into the engine-cylinder, a governor-valve in said passage-way, having a projecting stem, a suitably-supported cam 115

with means whereby it may be driven by operation of the engine, an adjustable arm arranged between said projecting stem and cam, a cylinder having communicating passage-way with the storage-tank, a compound valve in the latter passage-way, having an opening leading therefrom to the open air, a piston in the latter cylinder having an extended rod, rack-teeth on the said rod, a toothed segment loosely arranged on the engine power-shaft, a pawl carried by the toothed segment, with the same arranged for engagement with the ratchet-wheel teeth, the said rack and segment teeth being arranged for meshing engagement, a bell-crank having one end secured to the racked piston-rod, a rod extending from the bell-crank to the adjustable arm between the governor-valve and its operating-cam, whereby in operation of the engine, the arm is thrown into and out of operative position, and a separate passage-way leading from the tank into the engine-

cylinder, the latter passage-way having a check-valve therein, whereby to close return-flow into the engine-cylinder, substantially as 25 described.

3. The combination in an engine - starter, of a storage-tank, having communicating passage-way with the engine-cylinder, a governor-valve in said passage-way, a separate 30 passage-way providing communication between the tank and engine-cylinder, a check-valve in the latter passage-way, means whereby boosting action may be imparted to the engine power-shaft, means for the conveying and controlling of the booster motive power, and means controlling operation of the governor-valve, actuated by the means for imparting boosting action, substantially as 35 described.
